UNITED STATES PATENT OFFICE

2,478,537

MUSICAL INSTRUMENT AND SUPPORT
THEREFOR

William Karl Krause, Los Angeles, Calif.

Application September 4, 1945, Serial No. 614,419

3 Claims. (Cl. 84—280)

1

My invention relates to a musical instrument generally known as a bow zither, in that it has a zither-like arrangement of strings disposed above a finger board and is played by means of a bow drawn across said strings, and the principal object of my invention is, to provide simple and readily adjustable means for clamping a five stringed violin, which clamping means includes a finger board that overlies the finger board of said violin, further, to provide a vertically adjustable leg or standard for the violin clamping means and further, to provide the adjustable standard with adjustable braces adapted to be engaged by the knees of the player of the instrument.

With the foregoing and other objects in view, my invention consists in certain novel features of construction and arrangement of parts which will be hereinafter more fully described and claimed and illustrated in the accompanying drawings, in which:

Fig. 1 is a plan view of my improved musical instrument.

Fig. 2 is a side elevational view of the instrument.

Fig. 3 is an enlarged vertical section taken on the line 3—3 of Fig. 2.

Fig. 4 is a section taken on the line 4—4 of Fig. 3.

Fig. 5 is a horizontal section taken on the line 5—5 of Fig. 2.

Fig. 6 is an enlarged vertical section taken on the line 6—6 of Fig. 2.

Referring by numerals to the accompanying drawings which illustrate a preferred embodiment of my invention, 10 and 11 designate the upper and lower parts of a leg or standard and the adjacent end portions of said parts are threaded as designated by 10a and 11a so as to be screw seated in the ends of an internally threaded tube 12, so that when the latter is rotated, the length of the standard is increased or decreased.

The lower end of member 11 carries a shoe 13, preferably of rubber which is adapted to rest on the floor and to the upper member 10, is secured a block 14, in the top of which is formed a notch 15, having a convex bottom face 16.

Pivoted on a pin or bolt 17 which passes transversely through block 14, are plates 18, which depend from the sides of a finger board 19, the latter being concave-convex in cross section so as to fit snugly upon cover of the neck and finger board portion N of a violin such as V. This

2

violin or as it is generally termed by musicians "bow zither," has five strings S, which are supported by a bridge B on the violin body and a second bridge B' on the outer end of the finger board. A conventional violin or viola may be converted into a bow zither by adding to the peg box P' a fifth peg and adding a fifth string to the four strings of said violin or viola.

The strings are connected in conventional manner to tuning keys or pegs P, rotatively seated in peg box P'. Notched block 14 provides a saddle for supporting the neck of the bow zither in differently adjusted positions, and after plates 18, finger board 19 and engaged neck have been adjusted to the desired position, said plates are clamped to block 14 by a set screw 20, which passes through an arcuate slot 21 formed in one of said plates concentric with axis bolt 17 and said screw being seated in block 14 (see Fig. 3). 20 If desired, short wedges such as 22, may be driven into clamping position between the upper portions of plates 18, the finger board 19, the top of block 14 and the sides of the neck N, in order to more firmly secure the bow zither in its adjusted position on said block (see Figs. 3 and 4).

The split ends of short horizontal arms 23 are mounted for vertical and rotary adjustment on leg member 10 and clamped thereto by bolts 24 and the outer ends of said arms are padded as 30 designated by 25.

After the leg or standard has been adjusted to the proper height and the bow zither adjusted to the proper angle on the block 14, arms 23 may be adjusted on member 10, so as to enable the 35 pads 25 on said arms to be conveniently engaged by the knees of the seated player and thus the instrument is firmly held while being played.

Thus it will be seen that I have provided a simple, practical and readily adjustable means 40 for converting a violin or viola into a bow zither and for conveniently supporting same while being played.

Minor changes in the size, form and construction of the various parts of my improved musical instrument may be made and substituted for those herein shown and described without departing from the spirit of my invention, the scope of which is set forth in the appended claims.

I claim as my invention:

50 1. A support for bow zithers comprising an adjustable standard, a block on the upper end of said standard, an inverted U-shaped clamp carried by said block and a pair of horizontally dis-

posed knee engaging braces adjustably mounted on said standard.

2. The bow zither support as set forth in claim 1, which block is provided in its upper portion with a notch for reception of the neck of the bow zither and the bottom of which notch is convex lengthwise.

3. The bow zither support as set forth in claim 1, said clamp being mounted for tilting movement on said block and a set screw for securing said clamp in differently adjusted positions. 10

WILLIAM KARL KRAUSE.
